(57) **CLAIM**

The ornamental design for a welder enclosure, as shown and described.

DESCRIPTION

FIG. 1 is a front perspective view of a welder enclosure showing our new design;

FIG. 2 is another front perspective view, taken from top and right side thereof;

FIG. 3 is a rear perspective view thereof;

FIG. 4 is another rear perspective view, taken from the top and left side thereof;

FIG. 5 is another rear perspective view, taken from the bottom and right side thereof;

FIG. 6 is another rear perspective view, taken from the bottom and left side thereof;

FIG. 7 is a front elevation view thereof;

FIG. 8 is a rear elevation view thereof;

FIG. 9 is a left side elevation view thereof;

FIG. 10 is a right side elevation view thereof;

FIG. 11 is a top plan view thereof; and,

FIG. 12 is a bottom plan view thereof.

The broken lines show portions of a welder enclosure that form no part of the claimed design.

1 Claim, 12 Drawing Sheets
